(57) **CLAIM**

The ornamental design for a nursing multi-skill training pad, as shown and described.

DESCRIPTION

FIG. 1 is an isometric top view of a nursing multi-skill training pad according to the design;

FIG. 2 is an isometric bottom view thereof;

FIG. 3 right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines immediately adjacent to the shaded areas depict the bounds of the claimed design, while all other broken lines are directed to environment. The broken lines form no part of the claimed design.

1 Claim, 3 Drawing Sheets
